DISPLAY STAND

Jerome B. Linden and Jack Jungmeyer, Jr.,
Los Angeles, Calif.

Application June 8, 1953, Serial No. 25,362

Term of patent 14 years

(Cl. D80—9)

To all whom it may concern:

Be it known that we, Jerome B. Linden and Jack Jungmeyer, Jr., citizens of the United States, both residing at Los Angeles, in the county of Los Angeles and State of California, have invented a new, original, and ornamental Design for a Display Stand, of which the following is a specification, reference being had to the accompanying drawings, forming a part thereof.

Figure 1 is a perspective view of a display stand showing our new design; the same being in a closed position.

Figure 2 is a perspective view with the stand in an open position.

Figure 3 is a side elevational view, with the stand in a closed position.

Figure 4 is a front elevational view looking in the direction of the arrow 4 in Figure 2; and

Figure 5 is a side elevational view thereof looking in the direction of the arrow 5 of Figure 2, and showing the stand in an open position.

We claim:

The ornamental design for a display stand, substantially as shown.
